United States Patent Office.

GEORGE WILKINSON, OF PROVIDENCE, RHODE ISLAND.

Design No. 3,276, dated December 1, 1868.

DESIGN FOR A FORK OR SPOON-HANDLE.

The Schedule referred to in these Letters Patent and making part of the same.

To all whom it may concern:

Be it known that I, GEORGE WILKINSON, of the city and county of Providence, and State of Rhode Island, have originated a new Design for Articles of Silver and other Metals, and Plated Ware, of which the following is a full, clear, and exact description, reference being had to the accompanying drawings, making part of this specification; that is to say, a design called the "Fleur-de-lis," for the handle of forks, spoons, and other table-ware and implements, the outline of which is represented in Figure 1 of the drawings, Figure 2 representing a front and back view of said design.

In outline, the said handle widens gradually from its stem, *b*, near the spoon-bowl or fork, to the end of the blade *B*, which is ornamented with a fleur-de-lis, *F*, from which the design derives its name.

Claim.

I claim the design for handles of forks, spoons, &c., substantially as herein represented and described.

GEO. WILKINSON.
